UNITED STATES PATENT OFFICE

TH DE KONING, OF BROOKLYN, NEW YORK

MEANS FOR METER DIAL MARKING

Application filed May 15, 1925. Serial No. 30,521.

My invention relates to means for and method of marking dials, having particular relation to such dials as are employed in meters.

One object of my invention is to provide a method of marking dials which shall be substantially mechanical in operation so as to eliminate the dial marker and which shall permit a greater degree of accuracy in the dial marking than has heretofore been possible.

Another object of my invention is to provide means for and method of marking meter dials which is suitable for inexpensive quantity production methods of manufacture, involving a minimum expenditure of time and of money.

With these and other objects and applications in mind, my invention further consists in the details of construction and operation and arrangement, hereinafter described and claimed and illustrated in the accompanying drawings, wherein:—

Fig. 1 is a top plan view of the dial-marking device and calibration plate;

Fig. 2 is an end elevational view illustrating the dial-marking device, the calibration plate, the dial to be calibrated and the supporting plate;

Fig. 3 is a transverse sectional view taken on the line III—III of Fig. 1;

Fig. 4 is an enlarged, detail, top plan view of the dial-marking device and instrument to be tested, showing the instrument needle positioned in alignment with one of the major slots;

Fig. 5 is a detached perspective view of one of the minor blades;

Fig. 6 is a sectional view taken on the line VI—VI of Fig. 4;

Fig. 7 is a detail and elevational view of one of the adjusting tips shown in Fig. 4;

Fig. 8 is an enlarged, detail, top plan view of a modified form of dial-marking device;

Fig. 9 is a view similar to Fig. 8, but showing a still further modification;

Fig. 10 is a transverse sectional view taken on the line X—X of Fig. 9; and

Fig. 11 is a vertical sectional view taken on the line XI—XI of Fig. 9.

Referring to Figs. 1 to 7, inclusive, of the drawings, a fan-like dial-marking device 1 comprises an elongated expandable and contractable structure 2, the opposite ends of which are mounted on angularly disposed supporting members 3 and 4, the inner ends of which are secured to vertical sides 5 and 6, respectively, of a mounting member 7. The latter may comprise a horizontal base section 8 which is provided with a vertically extending shaft 9 constituting a common pivotal support for a plurality of blades 11 to be presently described.

A vertical movement of the strips 11 may be prevented by means of a clamping plate 12, the opposite edges of which are bent downwardly to form the supporting sides 5 and 6, the end of the latter being riveted to the horizontal base section 8. The ends of the base section 8 are provided with apertures 13 and 14 adapted to receive centering pins 15 and 16, respectively, of a base plate 17, hereafter referred to. The apertures 13 and 14 are also adapted to register with threaded holes (not shown) in a meter 18 (Fig. 4) to be tested, said threaded holes being designed to receive the clamping screws, whereby the dial-marking device may be detachably secured in position.

Referring more particularly to the construction of the elongated expandable structure 2, a plurality of transversely extending members 19 are interconnected by strips of cloth or other flexible material 21 so as to form a plaited structure of fan-like construction. For purposes of illustration, members one, six, eleven, sixteen, twenty-one, twenty-six, thirty-one and thirty-six will be hereinafter referred to as major blades 22, while the four members intermediate successive major blades 22, 22 will be referred to as minor blades 23.

The construction of the minor blades 23 is particularly illustrated in the detached perspective view of Fig. 5, wherein a U-shaped member 24 is provided with a base portion 25, side wall portions 26 and 27 and turned back edge portions 28 and 29, respectively. An outer end 31 of each minor blade 23 may be slidably supported by a curved rod

32 which passes through an aperture 33 therein. The ends of the curved member 32 are secured to the end supporting members 3 and 4. Inwardly of the perforation 33 is positioned a second perforation 34 for the reception of a resilient strip 35, the opposite ends of which are also extended to the end supporting members 3 and 4. The aperture 34 may be connected to the aperture 33 by a slot 36 in order to facilitate the insertion of the resilient element 35 into said aperture 34.

10 A similar aperture 37 is formed on an inner end 38 of each minor blade 23 for the reception of a resilient element 39, the opposite ends of which are also secured to the end members 3 and 4. A slot 41 serves to facilitate the insertion and removal of the resilient element 39 from the aperture 37. A portion 42 of the base portion 25 of the minor blade 23 is removed to provide an opening 43, for reasons as will appear more fully herein after.

15 The minor blade 23 may be reinforced by strips 44 and 45, which are positioned intermediate the side walls 26 and 27 of the member 24 on opposite sides of the opening 43. The strips 44 and 45 are provided with openings corresponding to the openings just referred to for the U-shaped member 24. The 20 folded strips 21 interconnecting successive minor blades 23 have their edge portions 46, 46 respectively clamped by the folded back edge portions 28 and 29 of successive minor blades 23. As illustrated in Fig. 6, the fabric 25 may be further secured in position by rivets 47.

20 The major blades 22 (Fig. 4) comprise side strips 48 and 49 which are spaced by intermediate strips 51 and 52. The adjacent ends of the strips 51 and 52 are spaced to form an opening 53 which is somewhat larger than the opening 43 in the minor blades 23. The edges of the strips of cloth 21 are secured to the side strips 48 and 49 by folded back edge portions 54 and 55 (Fig. 6) and by rivets 56, as in the case of the minor blades 23. The intermediate strip 51 constitutes one end of the blade 11 which is pivotally mounted on the pin 9, thereby affording a 25 support for the inner edge of the expandable structure 2. The remaining intermediate strip 52 is slidably mounted on the curved rod 32 and it is provided with a projecting portion 57 which extends through a slot 58 in a curved supporting strip 59, the opposite ends of which are respectively mounted on the supporting members 3 and 4. An inner surface 61 of the supporting strip 59 is serrated, as shown in Fig. 4.

30 An adjusting tip 62 is provided with a cylindrical portion 63 which embraces the projecting portion 57 and it terminates in an enlarged head portion 64, an inner surface 65 of which is formed complementarily to the surface 61 of the supporting strip 59. A

35 spring 66 extends between the strip 52 and the enlarged head portion 64, whereby the surfaces 61 and 65 may be resiliently retained in engagement. When the adjusting tip 62 is depressed to disengage the surfaces 61 and 65, the major blade 22 directly connected thereto may be moved about the pivot pin 9 as a center. For purposes of illustration, as shown only eight major blades are associated with the adjusted tips 62, but of course, any desired number may be employed depending upon the desired number of major division markings on the blank dial. As shown in Fig. 1, the present construction is adapted to provide eight major division lines on the blank dial and four minor divisions intermediate each pair of major division lines.

40 As previously stated this is for purposes of illustration only.

45 Inasmuch as the major and minor blades 22 and 23 are interconnected by the resilient elements 35 and 39 and slidably supported on the curved rod 32, an adjustment of any one of the major blades 22 automatically causes the distance between the minor blades 23 on one side thereof to increase in equal proportion and the distance between the minor blades 23 on the opposite side thereof to correspondingly decrease. The adjustment tips 2 may thus expand or contract the section 50 or groups of secondary blades 23 while maintaining the relative spacing between the blades 23 in each group substantially constant.

55 In the practical application of the dial-marking device above described, a blank dial 67 (Fig. 4) is mounted on the instrument 18 to be calibrated, said dial having an elongated slot 68 sufficiently wide to include between the edges thereof the slots or openings 43 and 53 in the minor and major blades 23 and 22, respectively. The length of the slot 68 is substantially equal to that of the standard scale. The dial-marking device 1 is now positioned on the blank dial 67 in such manner that the openings 13 and 14 in the mounting member 7 register with the openings (not shown) for the dial clamping screws, whereupon the latter screws are caused to clamp the parts just mentioned rigidly in 60 position. Assuming that a 0-70 ampere scale is to be made for the instrument 18, eight major blades 22 are needed. The first major blade to the left of the dial-marking device 1 is so moved by the adjusting tip 62 as to bring the opening 53 into alignment with the movable needle 69 of the instrument 18. When the adjusting tip 62 is released, further movement thereof is prevented by 65 the interlocking of the serrated surfaces 61 and 65 under the action of the spring 66.

70 A ten ampere current is next passed through the instrument 18 and the second adjusting tip 62 is actuated until the instru- 75

ment needle 69 is visible through the slot 53. Subsequently, the current is increased by steps of ten amperes up to seventy, the remaining adjusting tips 62 being successively actuated to bring the openings 53 thereof into alignment with the instrument needle 69. The final arrangement of the major marking blades 22 is that shown in Figs. 1 and 4. As a result of the interconnection 10 of the major and minor blades 22 and 23 by the resilient elements 35 and 39 respectively, the relative spacing of the minor blades 23 in each group is the same at the ends of the marking device 1, where the adjusting tips 15 62 are spaced relatively close, as in the center where the spacing of the adjusting tips 62 is relatively large.

The dial-marking device 1 is now removed from the instrument 18 and so mounted 20 on the supporting plate 17 that it may be centered by pins 15, 16 and 70 (Fig. 1), calibration plate 71 having an arcuate slot 72 of such dimensions as to include the slots 43 and 53 in the minor and major division 25 blades 23 and 22, respectively, is positioned intermediate the device 1 and the supporting plate 17. A blank dial 73 is also mounted on the supporting plate 17 directly beneath the calibration blades 72. The blank dial 73 30 may now be marked in accordance with the relative spacing of the slots or openings 43 and 53 on the dial-marking device 1 by spraying a marking substance, such for example, as ink into said slots. After the dial 35 73 has been thus marked, it may be mounted on the instrument 18.

Should it not be desirable to mark the blank dial 73 by the spraying method, a small brush may be employed to paint the 40 exposed surface of the dial 73 in line with the several openings 43 and 53.

A further method of marking the dial plate 73 involves the coating of the upper surface thereof with a light-sensitive material. 45 Since the plates 71 and 17 protect the sensitized coating as a whole, only such portions as are directly beneath the slots 43 and 53 are affected. To expedite this marking process, an auxiliary source of light (not shown) may 50 be mounted in proximity to the upper side of the dial-marking device 1.

A 0-70 ampere scale has been referred to in the above description, but should a 0-50 ampere scale be desired, then only six major 55 blades 22 would be required. The remaining major and minor blades 22 and 23 may be rendered ineffective by employing a calibration plate having a shorter slot than the slot 72 previously employed, said shorter slot being of a length substantially equal to that 60 of the scale of the instrument to be treated.

The modification shown in Fig. 8 is the complement of the preceding figures, and it 65 differentiates over the same in the removal of the protective strips 21 and the replacement

of the apertured major and minor blades 22 and 23 by solid blades 22a and 23a.

In operation, the adjusting tips 62 are actuated so as to align the major blades 22a with the instrument needle 69. Thereafter 70 the dial-marking device 1 is mounted on the calibration plate 71, the blank dial 73 and the supporting plate 17, and the device is then sprayed or painted or subjected to light 75 in accordance with the above described methods. The position of the blades 22a and 23a on the blank dial 73, however, will be represented by blank spaces rather than lines as in the preceding figures.

In Figs. 9 to 11, inclusive, is shown an alternative form of expansible and contractable structure 75 to that illustrated in the preceding figures, and the construction therein disclosed involves the use of a plurality of adjusting tips 76 for independently controlling the position of major openings or slots 77. The adjusting tips 76 comprise a body portion 78 which is slidably mounted in a groove 79 formed in a curved supporting strip 81 which corresponds to the strip 59 of Fig. 4. The main body portion 79 is provided with an outwardly projecting portion 82 which is movable in a restricted portion 83 of the groove 79. An outer end of the projecting portion 82 is threaded to receive a clamping nut 84 which may be caused to engage a resilient strip 85 on the outer surface of the supporting member 81. Thus when the nut 84 is turned so as to engage the resilient strip 85, the shoe or body portion 78 is clamped in position. 95

A second supporting strip 86 is mounted inwardly of the supporting strip 81 and it is provided with a longitudinal recess 87 for the reception of a slideable shoe 88 somewhat similar to the shoe 78. Each shoe is provided with inwardly extending cylindrical projections 89 constituting pintles, as will presently appear. A pair of blades 91 and 92 are mounted between the supporting strips 81 and 86 with the opposite ends thereof hinged on adjacent pairs of pintles 89, 89. The adjacent ends of the blades 91 and 92 are beveled, as shown in Fig. 9, and are interconnected by flexible strips 93 and 94. The adjacent ends of the blades 91 and 92 are also provided with recesses to form a major slot 95 which corresponds to the major slots 53 of the preceding figures. 110

The adjacent ends of the sections 91, 92, which are hinged on the pintles 89, are similarly recessed to provide the previously-mentioned slot 77. The portion of the blade or section 91 intermediate the major slots 77 and 95 are provided with, say, four slots 96, which correspond to the slots 43 in the minor blades 23, and the section 92 is similarly provided with slots 96. A strip of cloth 97 is glued or otherwise secured to the sections 115 120 125 130

91 and 92 so as to prevent the passage of the marking substance through the hinged portions thereof. The construction of the present modification may be otherwise as shown in Figs. 1 to 7, inclusive.

When one adjusting tip 76 is moved toward another, the sections 91 and 92 buckle, as illustrated in Figs. 9 and 10. However, the relative spacing of the slots 96 as defined by the projection thereof on the blank dial 73 remains substantially constant, and the same result obtains when the adjusting tip 76 is so moved as to flatten the sections 91 and 92. In operation, the adjusting tips 76 are actuated so as to bring the slots 77 successively into alignment with the instrument needle as it assumes the different positions.

When the major slots have been adjusted to the desired positions, the dial-marking device 1 is mounted as shown in Fig. 2 for the dial-marking device 1. Thereafter, the relative positions of the slots 77, 75 and 96 may be transferred to the blank dial 73 by the methods discussed in connection with the dial-marking device 1. If necessary the dial-marking device 1 may be made of non-magnetic and high resistance material.

The structure shown in Figs. 9 to 11 is susceptible of modification in much the same manner as previously set forth in connection with Figs. 1 to 7, and Fig. 8. For example, the sections 91 and 92 may comprise an open framework with blades (not shown) positioned thereon in accordance with the relative spacing of the slots 77, 95 and 96. The operation of such construction would be substantially as described in connection with Fig. 8.

While I have shown several forms of embodiment of my invention, for the purpose of describing the same and illustrating its principles of construction and operation, it is apparent that various changes and modifications may be made therein without departing from the spirit of my invention. I desire, therefore, that only such limitations shall be imposed thereon as are indicated in the appended claims or as are demanded by the prior art.

60 I claim:

1. A dial-marking device, comprising an expandable structure provided with a plurality of radially-extending portions having means therein for the observation of a movable member in proximity thereto, common pivotal mounting means for at least some of said portions, and means interconnecting said portions and maintaining relative spacing of the latter independently of the expansion of said structure.

2. A scale-marking device, comprising an expandable structure having a plurality of groups of openings therein, and means whereby the distance between the openings in each group may be increased while maintaining

substantially constant the relative spacing thereof.

3. An expandable structure having a plurality of main openings, means whereby the position of the said openings may be independently adjusted, said structure having one or more secondary openings intermediate a pair of main openings, and means for maintaining the proportional distances between the openings substantially unchanged when said structure is expanded.

4. A dial-marking device, comprising an expandable structure, said structure including a plurality of members having openings therein, means for guiding said members during an expansion, a track arranged adjacent said members, and means operatively associated with the extremities of certain of said members and movable along said track, for positively actuating said members.

5. An expandable and contractable structure including a plurality of elements having openings, and a track arranged adjacent the extremities of said elements for guiding the same during said expansion and contraction, said elements having co-axially mounted portions.

6. A dial-marking device, comprising an expandable structure including a plurality of radially-extending elements having openings therein for observation of a movable member in proximity thereto, a supporting framework for said structure, means for interconnecting said elements and said framework, whereby the position of said elements in a fixed arc may be adjusted, and a member for guiding said elements during said adjustment.

7. A dial-marking device, comprising a fan-like expandable structure provided with a plurality of radially-extending elements each having an opening, means whereby the relative spacing of said elements is independent of an expansion, the said elements being substantially unobstructed underneath whereby they are adapted to be so positioned that said openings are immediately adjacent to the path of travel of an instrument needle, and means for maintaining said elements in a fixed arc.

8. A fan-like structure, comprising an expandable portion provided with a plurality of radially disposed members having openings, certain of said members being extended radially inwardly, means affording a common pivotal support therefor, supporting means for said radially extending members, and means individual to certain of said radially extending members for independently adjusting the same.

9. A dial-marking device comprising an arcuate expandable and contractable structure having a plurality of radially disposed members having openings, certain of said members being extended inwardly, a member

affording a pivotal mounting therefor, rigidly disposed members extending from said mounting so as to engage the respective ends of said expansible structure, a rod extending between said last-mentioned members and operatively associated with said first-mentioned members, a second supporting member extending between said rigidly disposed members, and a plurality of adjusting knobs 10 slidably mounted on said second supporting member, said knobs being so associated with said radially extending members as to form the same into groups.

10. In a dial-marking device, an elongated arcuate expansible structure, comprising a plurality of radially extending members having openings therein, one end of said members having another opening for the reception of an elastic element, the other end of said members having an additional pair of openings, of which one is adapted to receive an elastic element and the other a guiding member.

11. In a device of the class described, a pair of spaced longitudinally extending supporting members, a plurality of pintles slidably mounted in said spaced members, the pintles on said members being disposed in pairs, and a pair of blades having the inner ends thereof flexibly interconnected and the outer ends mounted on a pair of said pintles, said blades having one or more openings.

12. In a dial-marking device, a plurality of resilient members and an elongated expansible structure having a plurality of members extending transversely with respect to said resilient members interconnected by said resilient members, the space intermediate successive members being open.

TH DE KONING.
